CLAIM

I claim the ornamental design for a ceramic fountain, as shown and described.

DESCRIPTION

FIG. 1 is a top perspective view of a ceramic fountain, showing my new design;

FIG. 2 is side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom view thereof.

Broken line elements are not claimed.

1 Claim, 4 Drawing Sheets# US D704,903 S
